COMBINED CAP AND DISPENSER FOR PRESSURIZED CONTAINERS

Robert Henry Abplanalp, 10 Hewitt Ave.,
Bronxville, N.Y.

Filed July 9, 1963, Ser. No. 75,715

Term of patent 14 years

(Cl. D58—26)

FIG. 1 is a perspective of a combined cap and dispenser for pressurized containers showing my new design.

FIG. 2 is a top plan view thereof on an enlarged scale.

FIG. 3 is an elevational view looking from the back of the structure shown in FIG. 1.

I claim:

The ornamental design for a combined cap and dispenser for pressurized containers, as shown.
